SPRAYING DEVICE

Milton S. Dunkelberger, Dayton, Ohio, assignor to
The American Display Company, Dayton, Ohio,
a corporation of Ohio

Application December 22, 1942, Serial No. 469,848

4 Claims. (Cl. 299—92)

This invention relates to a fluid pump mechanism and more particularly to a squirt gun.

Spray guns have been used quite extensively over a long period of time. In many of the spray guns that have been used, a system of check valves is utilized to control the flow of the fluid. Usually one check valve is located in the intake opening and another check valve is used in the outlet. One of these valves closes in response to the creation of a vacuum in the pump cylinder and the other operates in response to a pressure therein.

An object of this invention is to provide a dual-functional valve, so that the same valve member may be utilized for controlling both the intake and the outlet, the valve being so arranged that it permits filling of the pump rapidly through a large orifice or fluid passage and discharge of the fluid through a restricted opening simulating a nozzle, to thereby effectively discharge the fluid through this restricted opening under high pressure.

Another object of this invention is to provide a nozzle adapted for use either on a spray gun or a hose or any other place where a nozzle having a restricted opening is required, which nozzle permits the fluid to escape in a jet that may or may not be spread by an adjustable spreading mechanism, which mechanism may be adapted to project laterally into the stream or jet so as to disperse this jet as desired.

Other objects and advantages reside in the construction of parts, the combination thereof and the mode of operation, as will become more apparent from the following description.

In the drawing:

Figure 1 is a side elevational view of the spray gun mounted in association with the tank for holding a fire extinguishing fluid, spraying solution or any other fluid adaptable for use in the pump.

Figure 2 is a longitudinal, cross sectional view of the gun.

Figure 3 is a cross sectional view taken substantially on the line 3—3 of Figure 2.

Figure 4 is a cross sectional view of the valve member taken on the line 4—4 of Figure 2.

Figure 5 is a perspective view of a bracket adapted to support the spray gun.

Figure 6 is a side elevational view of the nozzle used with a conventional hose.

Referring to the drawing, the reference character 10 indicates a long tubular cylindrical member forming the cylindrical wall of the pump. At the upper end of member 10 there is

an end member 12 provided with a capping flange 14. Member 12 is provided with an opening for the pump rod or piston rod 16. The lower end of the cylindrical member 10 is provided with a threaded nipple 18 having threadedly securing thereto a nozzle member 20.

A rubber washer or gasket 22 is clamped between the end of the nipple 18 and a shoulder on the nozzle 20. The diameter of the aperture 10 in the washer or gasket member 22 is somewhat smaller than the adjacent diameter of the nozzle 20. The nozzle 20 is provided with a cylindrical cavity 24, terminating in a bevelled valve seat 26, having seated thereon, under certain conditions, a valve member 30.

This valve member 30 is provided with a valve stem 36 having a longitudinally extending bore 32 aligned with the aperture in the washer or gasket member 22 and aligned with the outwardly tapering nozzle portion 34 of the nozzle 20. The gasket member 22, in addition to sealing the nozzle 20 to the nipple 18, also provides a stop or retaining means for the valve member 30, so that when the valve member 30 is located in the cavity 24 and the nozzle is screwed into position on the nipple 18, the gasket member 22 provides an upper limit for the valve member. The valve member 30 is provided with a frusto-conical valve seat engaging head 40 seated upon the valve seat 26.

Means are provided for aligning the valve stem 36 with the center of the cylindrical cavity 24. This means forms a fluid passage around the valve, so as to permit the fluid to be drawn in very rapidly when the valve is unseated from the valve seat. In the particular embodiment shown, the valve stem 36 has been provided with a plurality of radially disposed arms or spacers 42. The arms or spacers 42 are arranged in spaced relation from the conical head 40 and are adapted to be positioned in the cylindrical cavity 24 of the nozzle 20. A second set of arms 44, substantially identical to those already described, is located in the extreme upper end of the valve member 30. The arms 42 and 44 cooperate to maintain the valve member in aligned relation with respect to the valve seat and in aligned relation with the normal flow of fluid through the nozzle, as will appear more fully later.

The lower or inner end of the rod 16 is threaded and supports a washer-like piston member 50, having mounted on either side a pair of leather or flexible washers 52 abutting retaining washers 54 held in position by a pair of nuts 56. These parts cooperate to form a piston. The upper end

of the rod 16 supports a D-handle 60, used to manually actuate the rod 16. In order to provide a cushion for arresting the upper movement of the piston, a cushioning spring 62 surrounds the upper end of the rod and is seated against an annular inwardly projecting boss on the end member 12. The upper end of the cylinder is provided with a plurality of vents 64 to permit the escape of air located above the piston.

In filling the spray pump, the lower end of the nozzle is submerged in the fluid to be sprayed. The rod 16 is withdrawn or raised in the cylinder 10, causing the piston members to create a vacuum in the lower end of the cylinder. As the fluid is drawn in through the lower end of the nozzle, the fluid raises the valve member 30, so as to unseat the valve portion 40 from the valve seat 26, permitting the fluid to pass rapidly along the sides of the valve member held in the central position by the arms 42 and 44. The fluid flows in the spaces between the arms. A small quantity of the fluid passes through the bore 32 of the valve member 30; but most of the fluid is drawn in around the sides of the valve member 30.

When the cylinder has been filled with liquid, the spray pump is ready for use. The piston rod is forced inwardly so as to force the piston against the fluid, pressure being supplied to the fluid, causing head 40 of the valve member 30 to be seated upon the valve seat 26, so as to restrict the flow of the fluid escaping from the gun to the fluid passing through the small orifice 32. By this arrangement, the fluid is discharged slowly under a comparatively large head.

As the fluid escapes through the nozzle, it may be dispersed or sprayed by a spray screw 70, having the inner end formed into a conical shape 72. The conical or pointed end of the screw may project into the stream discharged through the valve, so as to spread the stream, dividing it into a fine spray or mist. The screw 70 threadedly engages the side of the nozzle 34 and is limited in its outward movement by a stop member 74. When the screw is unscrewed so as to engage the stop member 74, the inner point of the screw does not come in contact with the stream or jet discharged through the valve.

This pump may be used as a fire extinguisher, utilizing either water or any other suitable fluid for extinguishing fire. Furthermore, the pump may be used in spraying fruit trees and plants, spraying stock dip and disinfectants, spraying paint and white-wash or any other suitable fluid that may be sprayed.

If the pump is used as a fire extinguisher, it may be used either with or without a tank. In the preferred embodiment shown in Figure 1, a tank 100 has been shown that tapers from bottom to top, so as to provide a wide base. Near the bottom of the tank 100 is a holster or pocket 102 receiving the nozzle of the spray pump when not in use. A suitable loop 104 surrounds the spray pump and is attached to the top of the tank. In order to facilitate the handling of the tank, it may be provided with a D-handle 106 and covered by a suitable lid 108 provided with a handle 110. The lid is preferably held in position by a suitable chain or flexible member 112.

The spray gun need not necessarily be used in connection with the tank, even though the spray gun may be used as a fire extinguisher. It may be hung in a bath room, near a tank of water, in the kitchen or any other desirable place. In order to support the spray gun it may

be provided with an annular collar 120 fixedly attached to the spray gun and provided with a suitable recess 122 receiving a tongue 124 of a bracket 126 fastened to a suitable support and provided with an arcuate seat 128 straddling the sides of the cylinder.

This collar 120, in addition to providing a support, is used as a hand grip ring. This permits the operator to get a good firm hold on the cylinder of the pump, without any danger of slipping.

Although the nozzle has been shown as a part of a spray pump, it may be used as a nozzle for a hose for sprinkling water and the like. In Figure 6 the nozzle has been shown attached to the end of a hose for spraying water. The type of a stream is determined by adjusting the screw 70.

Throughout the specification and claims 20 "spray gun," as applied to applicant's device, includes a squirt gun used to forcibly eject a stream of water, where it has not otherwise been limited to a device adapted to form a fine mist or spray.

25 Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

35 1. In a spray gun pump assembly, the combination of a cylinder and a piston mounted for reciprocatory movement in the cylinder, said cylinder terminating in a threaded nipple portion, with a nozzle assembly including a nozzle body member engaging the nipple, a gasket member mounted between the end of the nipple and a shoulder of the nozzle member for sealing the juncture between the nipple and the nozzle member, said gasket member having an aperture 40 smaller than the adjacent diameter of the nozzle member, said nozzle member having a restricted portion forming a valve seat, a duo-functional valve member mounted for reciprocatory movement between the valve seat and the gasket member, said valve member having a longitudinally extending bore registering with the opening passing through the restricted portion, and means for holding the valve member in spaced relation from the walls of the nozzle member, said means 45 permitting the flow of fluid around the valve member when water is drawn into the cylinder of the pump, said valve member being seated upon the valve seat when the fluid is expelled from the cylinder so as to restrict the flow of fluid to the fluid passing through the bore of the valve member.

50 2. In a spray gun pump assembly, the combination of a cylinder and a piston mounted for reciprocatory movement therein, said cylinder

65 terminating in a nipple portion, with a nozzle assembly including a nozzle body member, said nozzle member having a cylindrical cavity terminating in a reduced portion forming a restricted orifice merging into a flared flange portion,

70 a duo-functional valve member mounted for reciprocatory movement in the cavity, said valve member having a longitudinally extending bore registering with the restricted orifice, said valve member having a head engaging the reduced portion when in one position so as to permit

75

the escape of fluid only through the bore of the valve member, said valve member when unseated permitting the flow of fluid into the cylinder both through its bore and around the sides so as to permit the cylinder to be easily and quickly filled with the spray fluid.

3. In a spray gun pump assembly, the combination of a cylinder and a piston mounted for reciprocatory movement therein, said cylinder terminating in a nipple portion, with a nozzle assembly including a nozzle body member attached to the nipple portion, means for sealing the juncture between the nipple and the nozzle member, said nozzle member having a cylindrical cavity terminating in a reduced portion forming a restricted orifice, a duo-functional valve member mounted for reciprocatory movement in the cylindrical cavity, said valve member having a stem portion, a longitudinally extending bore passing through the entire valve member for registry with the restricted orifice, said valve member having a head adapted to engage the reduced portion of the nozzle member when in one position so as to permit the escape of fluid only through the valve bore mounted in registry with the restricted orifice, a plurality of radially disposed arms mounted upon the valve stem for holding the valve member in a centrally disposed position in the cylin-

drical cavity, said valve member when in unseated position permitting the flow of fluid into the cylinder of the spray gun both through the bore of the valve member and around the valve member to permit rapid and easy filling of the cylinder of the spray gun.

4. A nozzle assembly including a cylindrical main portion provided with a cylindrical cavity terminating in a reduced portion forming a restricted orifice, a valve member mounted in the cavity, said valve member being provided with a valve stem concentrically disposed with respect to the cylindrical cavity, a bore extending through the valve member, said bore registering with the reduced portion, said valve member having a head adapted to be seated upon the reduced portion when the valve member is in one position, means for holding the valve stem in concentric relation with respect to the walls of the cavity, 15 said means permitting the flow of fluid around the valve member when the fluid flows in one direction, said valve member head being seated upon said reduced portion in response to the flow of fluid in the opposite direction so as to permit 20 the fluid to be discharged only through the bore of the valve member when the fluid flows in this direction so as to form a jet.

MILTON S. DUNKELBERGER.
